WATER PURIFIER

Emanuel Stern, Mount Kisco, N.Y., assignor to
Dyneek Corporation, Port Chester, N.Y.

Filed Aug. 10, 1973, Ser. No. 387,246

Term of patent 14 years

Int. Cl. D23—01

U.S. Cl. D23—3

FIG. 1 is a perspective view of a water purifier showing my new design;

FIG. 2 is a front elevational view thereof;

FIG. 3 is a rear elevational view thereof;

FIG. 4 is a side elevational view thereof; and

FIG. 5 is a top plan view thereof.

I claim:

The ornamental design for a water purifier, as shown.
